United States Patent Office.

ABRAHAM G. JENNINGS, OF NEW YORK, N. Y.

Design No. 4,229, dated July 19, 1870.

DESIGN FOR A NET FABRIC.

The Schedule referred to in these Letters Patent and making part of the same.

To all whom it may concern:

Be it known that I, ABRAHAM G. JENNINGS, of the city, county and State of New York, have invented a new and original Design for Net Fabric; and I do hereby declare that the following is a full, clear, and exact description thereof, which will enable others skilled in the art to make and use the same, reference being had to the accompanying drawing forming part of this specification.

Figure 1 represents a face view of my new design for fabric.

Figure 2 is a detail enlarged face view of one pillar of the same.

Similar letters of reference indicate corresponding parts.

My invention relates to a design for a net fabric, which is formed of pillars of peculiar construction, that are united so as to form lozenge-shaped meshes, as hereinafter set forth.

There are two parallel threads, *a b*, stretched in the machine.

Between them is a zigzag warp-thread, *c*, carried alternately from one to the other of the threads *a b*, and secured thereto by two bobbin-threads, *d e*, which are wound spirally around the threads *a b*, as shown.

A series of such pillars, *A A*, is worked together to form a fabric with lozenge-shaped meshes, as shown in fig. 1.

I claim—

The design for a net fabric, formed of pillars constructed as herein described, which are united to form lozenge-shaped meshes, as set forth and shown.

A. G. JENNINGS.
